E. Ripley's Design for Stone Plates.

Fig. 2

Des. 180

Ezra Ripley, Troy, New York.
Letters Patent of 180. dated May 16th 1848
(assigned to A Cox & Co.)

The schedule referred to in these letters patent and making part of the same

To all to whom these presents shall come:

Be it known that I Ezra Ripley of Troy, in the County of Rensselaer, and State of New York, have invented or produced a new design for stove plates, and that the following is a full, clear and exact description of the same, reference being had to the accompanying drawings making a part of this specification in which

Fig 1 represents the front of an air tight parlor stove and Fig 2 the top plate - Plate Fig 1 has a gothic niche or recess marked Fig 2, and is ornamented with checkered work in its center, on either side of said niche is a bracket Plaster fig. 3, surmounted by a fancy cap, also a bold piece of Carved work on either side and below said niche fig 4.

Plate fig 3, is the top of a parlor stove, on which is shown a gothic panel marked fig 5. The margin is boldly carved and ornamented with check and bold work, all of which will more clearly appear by the drawings accompanying this description.

I claim as my invention and desire to secure by letters patent the above design which is fully set forth in the drawings accompanying this description.
